UNITED STATES PATENT OFFICE

136,337

DESIGN FOR A SHOE OR SIMILAR ARTICLE

Melville Kaufmann, Los Angeles, Calif.

Application December 12, 1942, Serial No. 109,023

Term of patent 3½ years

To all whom it may concern:

Be it known that I, Melville Kaufmann, a citizen of the United States, residing in the city of Los Angeles, in the county of Los Angeles, State of California, have invented a new, original, and ornamental Design for a Shoe or Similar Article, of which the following is a specification, reference being had to the accompanying drawing, forming a part thereof.

The essential features of my design are the platform, outsole and heel in the configuration and relationship shown in full lines.

I claim:

The ornamental design for a shoe or similar article, as shown and described.

MELVILLE KAUFMANN.
